CUSHION

John R. Meinwieser, New Providence, N.J., assignor to Better Sleep Inc., Berkeley Heights, N.J., a corporation of New Jersey

Filed Oct. 18, 1968, Ser. No. 14,067

Term of patent 14 years

Int. Cl. D6—01

U.S. Cl. D3—9

FIG. 1

FIG. 2

FIGURE 4 is an edge view looking from either top or bottom of FIG. 1.

I claim:

The ornamental design for a cushion, as shown and described.
